UNITED STATES PATENT OFFICE.

LINDON WALLACE BATES, OF MOUNT LEBANON, NEW YORK.

METHOD OF FIREPROOF-STORING MOBILE FUEL.

1,394,060.

Specification of Letters Patent.

Patented Oct. 18, 1921.

No Drawing.

Application filed August 5, 1919. Serial No. 315,563.

To all whom it may concern:

Be it known that I, LINDON W. BATES, a citizen of the United States, residing at Mount Lebanon, in the county of Columbia 5 and State of New York, have invented certain new and useful Improvements in Methods of Fireproof-Storing Mobile Fuel, of which the following is a specification.

This invention pertains to a method of 10 fireproof storing mobile fuel of the variety known as colloidal fuel, referred to in my application filed on or about August 5, 1919, Serial No. 315,497, said application being directed to the fuel and the method of producing the same.

It is well known that heretofore combustible liquids, such as fuel oils usable for fuel purposes have been stored subject to considerable danger owing to the inability to 20 quench with water a fire consuming them. The reason is that the most available and most commonly employed of this category of fuels have a specific gravity lighter than water, which means that they float on the 25 water and keep burning. The fire departments of cities and the fire underwriters require therefore that such oil fuels be stored under-ground, in limited quantities, in special tanks and at certain distances from 30 neighboring buildings. Such necessary precautionary restrictions have seriously handicapped the introduction of oil fuel into domestic use and industrial plants, especially in those located in cities.

35 Colloidal fuel as it is commercially known, is an adequately stable composite of liquid hydrocarbon and pulverized carbonaceous substances. In such composites, containing in some cases as little as about 15% by 40 weight of particles of carbonaceous substances, the specific gravity of the composite is greater than water. The following may be given as examples of such fuel: Colloidal fuel composed of 68½% navy fuel-oil from 45 Texas having a specific gravity of .924, 30% pulverized bituminous low volatile coal of specific gravity 1.4, and 11% of the fixateur described in the application mentioned gives a liquid product of specific gravity 1.03. 50 Colloidal fuel consisting of 40½% pressure still oil of gravity .960, 3% wax tailings, 15% road oils, 1½% fixateur, and 40% pulverized anthracite coal of specific gravity 1.8, gives a liquid product of specific gravity 55 1.32. A liquid composite of specific gravity 1.21 is made with 50½% pressure still oil, 3%

wax tailings, 15% petroleum pitch, 1½% fixateur and 30% pressure still coke of specific gravity 1.7.

It has been found from experience that 60 the stability character of colloidal fuel is such that during its "life," or a period of adequate stability, whose duration and degree are determinable and controllable within reasonable limits, the fuel may be kept 65 under a water seal. The components lighter than water do not separate during the period to the top of the seal to a noticeable or material extent. The water seal manifests consistently its operative character. So also, 70 a fire which is consuming colloidal fuel may be quenched with water.

Owing to the ability to store colloidal fuel under a water seal and to quench combustion with water, it is not necessary to take 75 the same precautions as are required in the case of an oil fuel lighter than water. As there is less danger of fire in the case of colloidal fuel stored under a water seal than in the case of liquid combustible not so 80 stored, there need not be the necessity, for example, of storage under-ground, or in specially constructed containers, or at as great a distance from other buildings. These restrictions and others may be justifiably re- 85 laxled to a considerable extent when colloidal fuel is concerned. The ability to store colloidal fuel under a water seal enables a mobile fuel to be introduced into cities without increasing the fire risk to the extent involved 90 in introducing oil fuel.

Having thus stated the nature of my invention, what I claim is:

1. That method of storing a stable mobile fuel comprising liquid hydrocarbon and pulverized carbonaceous substances where the specific gravity of the composite is greater than that of water, which consists in maintaining a water seal above the fuel whereby the water forms a separate layer on the top 100 surface only of the mobile fuel, thus protecting it from fire.

2. That method of preventing combustion during storage of a stable mobile fuel, comprising liquid hydrocarbon and pulverized 105 carbonaceous substance where the specific gravity of the composite is greater than that of water, which consists in placing such fuel within a container and pouring water thereon whereby the water forms a separate 110 layer on the top surface only of the fuel and thus protects the same from fire and whereby

the use of special protective apparatus or measure is rendered unnecessary.

3. That method of storing a stable mobile fuel comprising liquid hydrocarbon and pul-
- 5 verized carbonaceous substance where the specific gravity of the composite is greater than that of water, which consists in maintaining a water seal above the fuel, whereby the water forms a separate layer on the top
- 10 surface only of the mobile fuel and remains so placed during the storage of the fuel, thus protecting it from fire.
4. That method of storing a stable mobile fuel comprising liquid hydrocarbon and pul-

verized carbonaceous substance where the 15 specific gravity of the composite is greater than that of water, which consists in placing such fuel in a container and pouring water thereon whereby the water forms a separate layer on the top surface only of the fuel and 20 remains so placed during the storage of the fuel, thus protecting it from fire, and whereby the use of special protective apparatus or measures is rendered unnecessary.

In testimony whereof I have signed my 25 name to this specification.

LINDON WALLACE BATES.
